METHOD OF APPLYING TAR OR BITUMEN
TO ROAD SURFACES

Karl Dammann, Berlin, Germany

Application September 1, 1936, Serial No. 98,973
In Germany September 4, 1935

2 Claims. (Cl. 94—23)

This invention relates to a method of applying tar or bitumen to road surfaces.

It is well known that tar or bitumen is applied to the surface of roads to protect them against atmospheric influences and the ravages of traffic.

According to the methods hitherto in use, hot tar is applied to a road surface by means of pouring can or sprinkling machines in a finely distributed state, or by the employment of compressed air for atomizing and finely distributing it. Both methods are, however, open to the objection that the thin film of tar immediately cools off on coming into contact with the cold surface of the road and for this reason cannot thoroughly adhere thereto.

To overcome the foregoing objection is the aim of the invention and to this end the invention provides for the application to road surfaces of hot tar or bitumen from the bottom of a transported body of such material disposed in superimposed relation with respect to the road surface and within a mobile carrier and simultaneously with the application of a portion of such body to the road surface, the said portion is smoothed by the carrier and which overcomes the employment of brooms or other implements for smoothing. The main advantage of the invention is that the larger amount of tar held by the carrier prevents instant cooling of the applied portion by the road surface, and the heat of the applied material causes evaporation of moisture of the surface.

If the road has a relatively dense surface, such as a concrete or bitumen road, the method indicated above can be improved or rendered more effective in the following manner.

Concrete or bitumen roads must be very carefully built, in most cases not so much as to impart to them the necessary strength, but to make them dense enough to prevent the entrance of moisture which otherwise would destroy or impair them in winter time. In spite of greatest care this object is not always attained, and effective surface protection is therefore particularly important, though difficult to provide, since it is more difficult for the tar or bitumen to penetrate into the fine pores of the surfaces of the roads aforesaid than into the pores of the surfaces of a macadamized road.

The invention provides therefore for the arrangement of one or more suction devices within the mobile carrier, which may be of the vacuum cleaner type and disposed in front within the carrier so as to be surrounded by tar on all sides.

When these suction devices are connected with

a container of rarefied air, the air will be drawn out of the pores of the surface of the road and also in the immediate vicinity of the devices. Air from without cannot enter, as the suction devices are completely surrounded by tar. During travel of the carrier over the surface of the road atmospheric air pressure forces the tar into the pores of the surface which are closed more effectively than was possible heretofore.

The drawing illustrates a mobile apparatus capable of being used for carrying on the method in accordance with this invention, and in which:—

Fig. 1 is a side view of the apparatus, and

Fig. 2 is an enlarged perspective view of the carrier and suction devices upon an enlarged scale.

With reference to the drawing 1 indicates a boiler for the tar or bitumen and 2 a combined receiver and carrier element for the hot material which is to be applied to the road surface. The element 2 is of framewise form, open at its top and bottom, of rectangular contour and is to travel upon the road surface to which the hot material is to be applied. A supply pipe 3 extends from the boiler 1 and delivers the hot material from boiler 1 into the element 2 adjacent one end of the latter. The pipe 3 extends over the top edge of the said end of element 2. The boiler 1 is carried by a car 4 and also on the latter is mounted an air vessel 5 having associated therewith a vacuum pump. A suction line 6 leads from the vessel 5 through a tar separator 9 to a cross tube 7 arranged within the element 2. Carried by the tube 7 is a plurality of suction heads 8 which have their intakes in contact with the road surface to be treated when the apparatus is in use. That end of the element 2, over which the pipe 3 passes is suitably connected to the car 4. The bottom edges of the side and end walls of element 2 are provided with means, as at 10 to form a seal between the interior of element 2 and the portions of the road surface outwardly adjacent the side and end walls of element 2. The means 10 is formed of any suitable material, such as rubber. Figure 1 illustrates the element 2 supplied with a body of hot material 1 portions of which are to be applied to the road surface when traction is applied to element 2 and simultaneously with the application of the material, the latter is smoothed. When traction is applied to element 2, the vacuum pump coacts with the elements 5, 6 and 7 and 8 to provide for the drawing out of the air from the pores of the surface

which is to be treated by an application of the hot material.

I claim:—

1. A method of applying hot material possessing a characteristic to adhere to a road surface, said method comprising the step of moving a confined body of the said material while the later is subjected to atmospheric pressure across, and in contact with said surface, said step providing for successive follower bottom portions of said body adhering to said surface; simultaneously with the moving of said body across said surface, creating a continuous suction action on successive pores of said surface to evacuate the air therefrom in advance of the adhering of the said successive follower bottom portions of said body to the successive evacuated pores and with the suction created means covered by said body of material for preventing the re-entry of air into the air evacuated pores; and simultaneously with the adhering of the successive follower bottom por-

tions of said body in the evacuated pores, smoothing said portions.

2. An apparatus for applying hot surfacing material possessing an adhering characteristic to a road surface, said apparatus including a mobile combined receiving and carrying element for traveling on the road surface and for receiving a mass of the hot material, said element being in the form of a horizontally disposed rectangular frame having an open bottom and opening at the top 10 into the atmosphere, said frame including side and end walls for confining the said mass therein, said frame being provided with sealing means throughout the bottom surfaces of its side and end walls, and a suction creating means bodily 15 moving with said element, said means being covered by the confined mass and traveling upon the road surface at points of the latter disposed in spaced relation with respect to the ends of the frame.

KARL DAMMANN.
